(57) **CLAIM**

The ornamental design for a vehicle license frame having a design of skulls with illuminated eyes, as shown and described.

DESCRIPTION

FIG. 1 is a front elevational view of a vehicle pedal showing my new design. The broken lines indicate electrical wires for illuminated eyes. They are for illustration purposes only and form no part of the claimed design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.
